UNITED STATES PATENT OFFICE.

JAMES McALEAR, OF CHICAGO, ILLINOIS.

VACUUM-PRODUCING DEVICE.

1,367,556.

Specification of Letters Patent.

Patented Feb. 8, 1921.

Application filed December 31, 1915. Serial No. 69,537.

To all whom it may concern:

Be it known that I, JAMES McALEAR, a citizen of the United States, residing at Chicago, in the county of Cook and State of Illinois, have invented a certain new and useful Improvement in Vacuum-Producing Devices, of which the following is a specification.

This invention relates to vacuum producing devices and has for its object to provide a new and improved device of this description.

The invention is illustrated in the accompanying drawings, wherein—

15 Figure 1 is a view showing one form of device embodying my invention;

Fig. 2 is an enlarged view showing the controlling apparatus for controlling the liquid for operating the main valves;

20 Fig. 3 is a sectional view taken on line 3—3 of Fig. 2;

Fig. 4 is a sectional view taken on line 4—4 of Fig. 3;

25 Fig. 5 is a sectional view taken on line 5—5 of Fig. 4.

Like numerals refer to like parts throughout the several figures.

In carrying out my invention I provide a vacuum tank or chamber 1 adapted to be connected by a pipe 2 with a device, such as the heating apparatus, with which the vacuum producing device is used. The vacuum tank is provided with a steam inlet pipe 3 and a water inlet pipe 4, by means of which steam or water may be admitted to the tank. The steam inlet pipe is controlled by a valve 5 connected with a valve stem 6. The pipes 2, 3 and 4 connect with the case 5^a. This case is provided with a partition 5^b as shown, and the pipe 4 connects on one side of the partition and the pipes 2 and 3 on the other side. The case 5^a communicates with the chamber 1. The valve stem is provided at its upper end with an engaging piece 7 and a spring 8 surrounds the upper end of the valve stem and engages said engaging piece and a movable stop piece 9, said spring tending to open the valve. The adjustable piece 9 is slidably mounted upon rods 10 connected with the casing 11 containing a diaphragm for controlling the valve 5. This diaphragm has connected therewith a part 12 which engages the engaging piece 7. The casing 11 is arranged so that there is a space both above and below the diaphragm 13 therein. The space below the diaphragm is

connected by a pipe 14 with the pipe 2, which connects with the vacuum tank so that when there is a vacuum in the tank there will also be a vacuum beneath the diaphragm 13. Since the pipe 14 connects with the casing 11 below the diaphragm it is necessary to have a closed bottom to said casing and the part 12 therefor passes up through a stuffing box 12^a so that the desired condition may be maintained in the casing 11 below the diaphragm. The space in the casing 11 above the diaphragm is connected by a pipe 15 with a water pipe 16 leading to the casing 17 containing the controlling valve which admits or shuts off water from said pipe, the water coming from the supply pipe 18 connected with any suitable source of supply, such as the city water pressure or the like. The water pipe 4 is provided with a valve 19 by means of which it is controlled. The casing of the valve 19 is also connected with the hollow part 5^a which communicates with the tank 1. This valve is connected with the valve stem 20 which is moved by a diaphragm 21 in the casing 22. A spring 23 surrounds the valve stem and engages the diaphragm at one end, the other end engaging an adjustable stop piece 24 movably mounted on the rods 25. Since the under side of the diaphragm 21 is subjected to atmospheric pressure the casing 22 is simply provided with an opening at the bottom and the spring 23 passes through this opening and directly engages the diaphragm or a washer connected therewith, it being unnecessary to use an engaging piece similar to the engaging piece 7 shown in connection with spring 8. The casing 22 is provided with a space or chamber above the diaphragm, which is connected by a pipe 26 with the water pipe 16 so that water may be admitted above said diaphragm. When the valve 19 is open the water from the water pipe 4 passes into the tank 1, preferably through a pipe 27, and strikes a spraying device 28 so as to be sprayed about said tank. The tank 1 is provided with a discharge pipe 29 having a check valve 30 and discharging into a trap 31 provided with the partition 32 which acts as a water seal. This trap is provided with a discharge pipe 33, which leads to the sewer or back to the boiler or to any other point desired. Located above the trap 31 is a casing 34 containing a thermostatic device 35, which in the present case is shown as a

corrugated diaphragm containing a fluid which expands when heated. The steam and heat from the trap 31 is free to pass upwardly into the casing 34 so as to heat the 5 thermostatic device and cause it to expand. The casing 34 has connected therewith a discharge pipe 36 through which this vapor may pass from the casing. When the fluid in the thermostatic device 35 expands the 10 top of the device rises, and when this fluid contracts, the top of the device lowers. Connected with the top of the thermostatic device is a lever 37 (see Figs. 2 and 3). This lever is connected to a shaft 38, which passes 15 into the casing 17, there being connected to said shaft a lever 39 located in the casing 17. Some suitable packing device is arranged in connection with the shaft 38. As herein shown, this shaft is provided with a bevel 20 face 40, which engages a bevel face 41 on the casing, the two bevel faces being held together by a spring 42 which engages the lever 37 and a part on the casing, thus forming a packing device for the shaft. The wa- 25 ter pipe 18 connects with the top of this casing and there is a discharge pipe 43 connected with the bottom of the casing and with the trap 31. The lever 39 is connected with a valve 44, which controls the admission and 30 discharge of the water or other power fluid from the casing 17. Any suitable valve for this purpose may be used. As herein shown, the valve 44 is provided with the end piece 45, which slides in the part 46 pro- 35 vided with one or more discharge openings 47 communicating with the casing 17. When the end piece 45 is in the position shown in Fig. 4, the openings 47 are closed and the water is cut off from the casing 17. 40 When this end piece is moved downwardly past said openings, communication is made between the water pipe 18 and the casing 17. The valve is provided at the other end with the end piece 48, which slides in the piece 49 45 having one or more openings 50 communicating with the casing 17. When the end piece 48 is in the position shown in Fig. 4, the casing 17 is in communication with the discharge pipe 43 so that the fluid may pass 50 therefrom. When the end piece 48 is moved downwardly to cover these openings 50 the discharge from the casing is closed. A spring 51 is associated with the valve 44 and normally tends to hold it in a position where 55 the water is shut off from the pipe 18. This spring assists in returning the valve to this position when the thermostatic device is cool, and helps to take the load off of the thermostatic device due to the weight of the 60 valve. The pipe 16, which leads to the controlling apparatus for the main valve, connects with the casing 17 so that when the casing is connected with the pipe 18, water will flow to these controlling devices. A 65 pipe 52 leads from the pipe 16 to the casing

34 and projects into said casing (see Fig. 3), so that when water passes into the pipe 16 some of this water will pass through the pipe 52 and be discharged upon the thermostatic device, said pipe having openings 52^a 70 in it for this purpose located above the thermostatic device. The pipe 52 is provided with a controlling valve 53 having a stem 54, by means of which it may be controlled so as to vary the amount of water 75 entering the pipe 52, thereby varying the time required to cool the thermostat and hence the time required to close the valve 44. This valve 53 is preferably protected by a sleeve 55 and is set when the device is in- 80 stalled. If it is desired to shorten or lengthen the interval between the opening and closing of the valves 5 and 19, the valve 53 is adjusted to increase or decrease the amount of water entering the pipe 52. 85

I have described in detail a particular construction embodying my invention, but it is evident that the parts may be varied in many particulars without departing from the spirit of the invention as set out in the 90 appended claims, and I therefore do not limit myself to the particular construction illustrated.

The use and operation of my invention are 95 as follows:

When the device is installed and ready for operation, the valve 5 is held open by the spring 8 and the valve 19 held closed by the spring 23. Steam is now admitted through pipe 3 to the vacuum tank 1. This steam drives out the air and when the tank is full 100 of steam, the steam passes through the discharge pipe 29 into the trap 31 and then up into the casing 34, and comes into contact with the thermostatic device 35. The ther- 105 mostatic device then expands and moves the lever 37 so as to rock the shaft 38. This rocking of the shaft moves the lever 39 downwardly (see Fig. 2) so as to move the valve 44, (see Fig. 4) and bring the end 110 portion 45 below the openings 47. Water then enters the casing 17 through the pipe 18 and passes out through the pipe 16 and thence through the pipes 15 and 26 to the casings 11 and 22 above the diaphragms 115 therein. The diaphragm 13 is moved downwardly so as to move the valve 5 downwardly and close the steam pipe 3. The diaphragm 21 moves the valve 19 downwardly so as to open the water pipe 4. Water then passes 120 into the tank 1 and is sprayed throughout said tank so as to condense the steam therein, thereby producing a vacuum in the tank, and a suction through the pipe 2 so as to draw air from the steam system or other ap- 125 paratus in connection with which the device is used the air passing down through the pipe 2 and the hollow part 5^a into the tank 1. In the meantime water is also passing through the pipe 52 and is being discharged 130

upon the thermostatic device 35. This cools the thermostatic device and the arrangement is so timed that when the desired vacuum is produced in the tank 1 the thermostatic device is cooled so as to move the levers 37 and 39 and shaft 38 in the opposite direction so as to lift the valve 44 and disconnect water pipe 18 from the casing and open the discharge openings 50 so as to 5 connect the casing 17 with the discharge pipe 43. The water in the casings 11 and 22 above the diaphragms therein, is then discharged through pipe 16 and casing 17 and discharge pipe 43 into the trap 31. The 10 spring 23 then moves the valve 19 to its closed position, thereby shutting off water from the tank 1. In view of the fact that the tank 1 and pipe 2 are connected to the casing 11 below the diaphragm 13 by pipe 15 14 the vacuum therein will be exerted in the space in the casing 11 below the diaphragm and will hold the diaphragm against the action of the spring 8 so as to hold the valve 5 closed. When the vacuum falls to a pre- 20 determined point, the spring 8 then acts to open the valve 5. Steam then enters the tank 1 and drives out the air and water therein, and the action above described is then repeated. It will be seen that by means 25 of this apparatus the main valves for controlling the steam and water supply to the tank 1 may be easily and effectively controlled by connecting the apparatus with the ordinary city water system.

35 I claim:

1. A vacuum producing device comprising a vacuum receptacle, a steam connection leading thereto, a valve for controlling said steam connection, a water connection leading 40 to said receptacle, a valve for controlling said water connection, separate diaphragms for said steam and water valves, separate casings for said diaphragms, a source of water supply, a connection between said 45 source of water supply and said casings, so that the pressure of the water may be applied to said diaphragms, an automatic controlling device for controlling the admission of water to and the discharge of water from 50 said casings, and an actuating device for said controlling device, responsive to conditions in said vacuum receptacle.

2. A vacuum producing device comprising a vacuum receptacle, a steam connection leading thereto, a valve for controlling said steam connection, a water connection leading to said receptacle, a valve for controlling said water connection, separate diaphragms for said steam and water valves, separate 55 casings for said diaphragms, a source of water supply, a connection between said source of water supply and said casings, so that the pressure of the water may be applied to said diaphragms, a controlling device 60 for controlling the admission of water to said casings, and the discharge therefrom, consisting of a chamber, a valve in said chamber, a communication between the casing and the source of water supply controlled by said valve, a communication between said chamber and the connection leading to the casings containing said diaphragms, an actuating device for said valve, comprising a thermostat operatively connected therewith, a casing inclosing said 65 125

to said casings, and the discharge therefrom, consisting of a chamber, a valve in said chamber, a communication between the casing and the source of water supply controlled by said valve, a communication between said chamber and the connection leading to the casings containing said diaphragms, an actuating device for said valve, comprising a thermostat operatively connected therewith, a casing inclosing said 70 75

thermostat, and a connection between said vacuum receptacle and said casing, so that steam may pass from the receptacle to the casing. 80 85 90 95 100

3. A vacuum producing device comprising a vacuum receptacle, a steam connection leading thereto, a valve for controlling said steam connection, a water connection leading to said receptacle, a valve for controlling said water connection, separate diaphragms for said steam and water valves, separate casings for said diaphragms, a source of water supply, a connection between said source of water supply and said casings, so that the pressure of the water may be applied to said diaphragms, a controlling device for controlling the admission of water to said casings, and the discharge therefrom, consisting of a chamber, a valve in said chamber, a communication between the casing and the source of water supply controlled by said valve, a communication between said chamber and the connection leading to the casings containing said diaphragms, an actuating device for said valve, 105

comprising a thermostat operatively connected therewith, a casing inclosing said thermostat, a connection between said vacuum receptacle and said casing, so that steam may pass from the receptacle to the casing, and a discharge leading from said chamber controlled by the valve within the chamber. 110 115 120 125 130

4. A vacuum producing device comprising a vacuum receptacle, a steam connection leading thereto, a valve for controlling said steam connection, a water connection leading to said receptacle, a valve for controlling said water connection, separate diaphragms for said steam and water valves, separate casings for said diaphragms, a source of water supply, a connection between said source of water supply and said casings, so that the pressure of the water may be applied to said diaphragms, a controlling device for controlling the admission of water to said casings, and the discharge therefrom, consisting of a chamber, a valve in said chamber, a communication between the casing and the source of water supply controlled by said valve, a communication between said chamber and the connection leading to the casings containing said diaphragms, an actuating device for said valve, comprising a thermostat operatively connected therewith, a casing inclosing said

thermostat, a connection between said vacuum receptacle and said casing, so that steam may pass from the receptacle to the casing, a discharge leading from said chamber controlled by the valve within the chamber.

5. A vacuum producing device comprising a vacuum receptacle, a steam connection leading thereto, a valve for controlling said steam connection, a water connection leading to said receptacle, a valve for controlling said water connection, separate diaphragms for said steam and water valves, separate casings for said diaphragms, a source of water supply, a connection between said source of water supply and said casings, so that the pressure of the water may be applied to said diaphragms, an automatic controlling device for controlling the admission of water to and the discharge of water from said casings, an actuating device for said controlling device, responsive to conditions in said vacuum receptacle, and a connection between said vacuum receptacle and one of the casings containing one of said diaphragms, said latter connection communicating with the casing on the side of the diaphragm opposite to that with which the connection from the source of water supply communicates.

30 6. A vacuum producing device comprising a vacuum receptacle, steam and water connections leading to said vacuum receptacle, separate valves for controlling said steam and water connections, diaphragms for said valves, and means for automatically admitting a power fluid to said diaphragms to operate them, said power fluid actuating said diaphragms to alternately open one valve and close the other valve so as to connect and disconnect said steam and water connections with said vacuum receptacle in response to the conditions in said vacuum receptacle, and means for moving said valves in said steam and water connections 45 in a direction opposite to the movement thereof produced by said diaphragms.

7. A vacuum producing device comprising a vacuum receptacle, steam and water connections leading to said vacuum receptacle, 50 separate valves for controlling said steam and water connections, diaphragms for said valves, means for automatically admitting a power fluid to said diaphragms to operate them, said power fluid actuating said diaphragms to alternately open one valve and close the other valve so as to connect and disconnect said steam and water connections with said vacuum receptacle in response to the conditions in said vacuum receptacle and 55 means for reducing the pressure on one side of the diaphragm controlling the steam valve so as to make it substantially correspond to the reduced pressure in the vacuum receptacle, whereby the opening of the steam valve

is delayed until the pressure in the vacuum 65 receptacle reaches a pre-determined point.

8. A vacuum producing device comprising a vacuum receptacle, a steam connection leading thereto, a valve for controlling said steam connection, a water connection leading to said receptacle, a valve for controlling said water connection, separate diaphragms for said steam and water valves, separate casings for said diaphragms, a source of water supply, a connection between said source of water supply and said casings so that the pressure of the water may be applied to said diaphragms, a controlling device for controlling the admission of water to said casings and the discharge 80 of water therefrom, consisting of a chamber, a valve in said chamber, a communication between the casing and the source of water supply controlled by said valve, a communication between said chamber and 85 the connection leading to the casings containing the diaphragms, an actuating device for said valve in said chamber, and an actuating device for said valve responsive to conditions in said vacuum receptacle, 90 whereby water is admitted to said diaphragms so as to close the steam valve and open the water valve.

9. A vacuum producing device comprising a vacuum receptacle, a steam connection leading thereto, a valve for controlling said steam connection, a water connection leading to said receptacle, a valve for controlling said water connection, separate diaphragms for said steam and water valves, separate casings for said diaphragms, a source of water supply, a connection between said source of water supply and said casings so that the pressure of the water may be applied to said diaphragms, a controlling device for controlling the admission of water to said casings and the discharge of water therefrom, consisting of a chamber, a valve in said chamber, a communication between the casing and the source of water supply controlled by said valve, a communication between said chamber and the connection leading to the casings containing the diaphragms, an actuating device for said valve in said chamber, an actuating device 115 for said valve responsive to conditions in said vacuum receptacle, whereby water is admitted to said diaphragms so as to close the steam valve and open the water valve, and means for automatically moving the 120 valve in said chamber so as to shut off the water from said diaphragms and permit the discharge of the water therefrom after the water valve has been opened a pre-determined time.

10. A vacuum producing device comprising a vacuum receptacle, a steam connection leading thereto, a valve for controlling said

- steam connection, a water connection leading to said receptacle, a valve for controlling said water connection, separate diaphragms for said steam and water valves, 5 separate casings for said diaphragms, a source of water supply, a connection between said source of water supply and said casings so that the pressure of the water may be applied to said diaphragms, a controlling device for controlling the admission of water to said casings and the discharge of water therefrom, consisting of a chamber, a valve in said chamber, a communication between the casing and the source of 10 water supply controlled by said valve, a communication between said chamber and the connection leading to the casings containing the diaphragms, an actuating device for said valve in said chamber, an actuating device for said valve responsive to conditions in said vacuum receptacle, whereby water is admitted to said diaphragms so as to close the steam valve and open the water valve, means for automatically moving the valve in said chamber so as to shut off the water from said diaphragms and permit the discharge of the water therefrom after the water valve has been opened a predetermined time, and 25 means for varying the length of time said water valve is open.
11. A vacuum producing device comprising a vacuum receptacle, a steam connection leading thereto, a valve for controlling such steam connection, a water connection leading to such receptacle, a valve for controlling said water connection, separate controlling parts for controlling said steam and water valve, separate casings for said controlling parts, a source of water supply, a connection between said water supply and said casings so that the pressure of the water may be applied to said controlling parts, and automatic means for alternately inserting and withdrawing water from said casings.
12. A vacuum producing device comprising a vacuum receptacle, steam and water connections leading thereto, a valve for controlling each of said connections actuating parts therefor, a source of water supply, mechanism for applying the pressure of said water from said source of water supply to the actuating parts for said valves to open and close said valves to connect and disconnect said steam and water connections with said vacuum receptacle, and an automatic controlling device for said mechanism.
13. A vacuum producing device comprising a vacuum receptacle, steam and water connections leading thereto, a valve for controlling each of said connections, actuating parts therefor, a source of water supply, mechanism for applying the pressure of said
- water to the actuating parts for said valves 65 to open and close the valves to alternately connect and disconnect said steam and water connections with said vacuum receptacle to move them, in one direction and devices for moving said valves in the opposite direction, an automatic controlling device for said mechanism, a thermostatic actuating device for actuating said controlling mechanism, a casing for said thermostatic actuating device, and a communication between 70 said casing and said vacuum receptacle.
14. A vacuum producing device comprising a vacuum receptacle, steam and water connections to said vacuum receptacle, separate valves for controlling said steam and 80 water connections, actuating devices for said valves, means for admitting a power fluid to said actuating devices to operate them, said power fluid actuating said diaphragms to alternately open one valve and 85 close the other valve so as to connect and disconnect said steam and water connections with said vacuum receptacle in response to the conditions in said vacuum receptacle, and means for reducing the pressure on one 90 side of the actuating device of the steam valve so as to make it substantially correspond to the reduced pressure in the vacuum receptacle whereby the opening of the steam valve is delayed until the pressure in the 95 vacuum receptacle reaches a predetermined point.
15. A vacuum producing device comprising a vacuum receptacle, a steam connection leading thereto, a valve for controlling said 100 steam connection, a water connection leading to said receptacle, a valve for controlling said water connection, separate diaphragms for said steam and water valves, separate casings for said diaphragms, a 105 source of water supply, a connection between said water supply and said casings so that the pressure of the water be applied to said diaphragms, and automatic means for alternately inserting and withdrawing 110 water from said casings to move said valves in one direction, and means responsive to conditions in said receptacle for holding said steam valve closed independent of the pressure of the water in the casing thereof 115 until the vacuum in said receptacle has fallen below a predetermined point and means for returning said valves to their initial positions after they are moved by said diaphragms.
- In testimony whereof I affix my signature in the presence of two witnesses this 8th day of December, 1915.
